UNITED STATES PATENT OFFICE.

FREDERICK W. COLE, OF NEWTON, MASSACHUSETTS, ASSIGNOR OF ONE-HALF TO MOSES G. CRANE, OF SAME PLACE.

ELECTRO-MAGNET AND ARMATURE.

SPECIFICATION forming part of Letters Patent No. 403,517, dated May 21, 1889.

Application filed May 24, 1888. Serial No. 274,950. (No model.)

To all whom it may concern:

Be it known that I, FREDERICK W. COLE, of Newton, county of Middlesex, State of Massachusetts, have invented an Improvement in 5 Electro-Magnets and Armatures, of which the following description, in connection with the accompanying drawings, is a specification, like letters on the drawings representing like parts.

10 The object of my invention is to produce an electro-magnet and armature, which latter may be strongly attracted through a long range of movement, thus giving a powerful movement to the armature through a large angle upon its pivot, so that it may be used for many purposes where a mechanical operation involving some considerable expenditure of power is produced by an electric current. It is impracticable to perform such operations by electro-magnets of moderate sizes 15 of the usual construction, owing to the fact that the attractive power diminishes rapidly as the distance of the armature from the poles increases, so that with an ordinary flat-pole magnet and armature a movement of much extent cannot be efficiently produced.

The present invention is embodied in an electro-magnet of the usual horseshoe type, having its two poles side by side and similarly 20 shaped, combined with a pivoted armature and retractor therefor, said armature being pivoted on an axis parallel to the line joining the two poles, and the armature and polar extensions being so shaped that a portion of the 25 armature moves laterally along or substantially parallel with a surface of the pole extension, so that the actual distance between the adjacent surface of the armature and pole-piece is small in amount and varies but slightly 30 in different positions of the armature, although the mass of said armature as a whole approaches the poles of said magnet under the attractive influence thereof and is removed from said pole under the action of the retractor when said attractive influence is removed. In addition to the portion of the armature that thus moves laterally by the surface of the polar extension or through the magnet-field, the armature may also 35 have a portion which moves toward and from a corresponding surface of the magnet-poles

in substantially the usual manner, thus giving the magnet increasing power while the armature approaches, as may be desirable for certain uses to which the armature and magnet may be put.

Figure 1 is a side elevation of an electro-magnet and armature embodying this invention; Fig. 2, a front elevation thereof; Fig. 3, a rear elevation of one of the pole-pieces shown in Fig. 1, and Fig. 4 a modification to be referred to.

The main body of the magnet, consisting of the cores *a*, upon which are wound the coils *b*, of insulated wire, and the back strap, 65 *a'*, connecting the said cores, may be of usual character, the invention relating especially to the construction of the pole-pieces *c* and the armature *d* co-operating therewith. The said pole-pieces *c* or enlarged extensions of the 70 projecting ends of the cores are shown in this instance as having a flat surface, *c'*, inclined to the axis of the cores, and a curved surface, *c*², which should be substantially concentric with the axis upon which the armature *d* has 75 its pivotal movement for most purposes.

As shown in Figs. 1 and 2, the said armature is pivoted at *e* directly upon the said poles, which are provided with lugs or hinge 80 projections *f* to receive the pivot-pins, which pass through supporting-arms or brackets *g* attached to the armature *d*, the arms *g* being of brass or other non-magnetic material, so as not to close a magnetic circuit between the poles of the magnet.

The armature or part moved by it may be weighted, so as to be retracted by gravity alone, as shown in Fig. 4, or a retracting-spring may be provided, as shown at *h*, Fig. 1.

The armature *d* is composed of a portion, 90 *d'*, which is preferably curved so as to be substantially concentric with the axis *f*, about which it moves, and parallel, or nearly, so with the surface *c*² of the pole, so that in a movement of the armature toward and from the 95 magnet—that is, between the full to the dotted line position—the armature moves along the side of the pole instead of moving toward and from it, as in magnets of usual construction.

By having the sides *c'* *c*² of the pole inclined to the axis of the core the magnetic strength

increases toward the extremity or intersection of said surfaces, as indicated by the shading, Fig. 1, and when the armature is in its retracted position (shown in dotted lines) a 5 portion of said armature is still very near the pole of the magnet, so as to be strongly attracted, and when arranged with relation to the poles, as shown in Fig. 1, it is powerfully moved by the attraction of the magnet through 10 an arc of about forty-five degrees with as great a power as an armature of usual construction pivoted in the usual manner is moved through a very small arc.

The relation of the mass of the curved portion 15 d' of the armature to the pole is such that when near the attracted position (shown in full lines, Fig. 1) the magnetic attraction operates with diminishing effect, as the portion of the pole near the extremity tends to 20 draw the armature outward or toward its retracted position; but when it is required to give the magnet increased power upon the armature as the latter is drawn up this is accomplished by making the armature with 25 another portion, d^2 , that approaches the inclined face c' in substantially the same manner as an armature of usual construction. In the retracted position the portion d^2 is practically out of the field of attraction, but the 30 portion d' is then close to the tip or strongest portion of the pole, and is thus acted upon powerfully, and as the portion d' approaches the full-line position, Fig. 1, in which the tip of the pole has less tendency to draw the said 35 portion d' inward, the portion d^2 comes into the field and is strongly attracted, thus making the entire movement of the armature very powerful.

The specific shape shown in Fig. 1 is not essential, and the shape may be modified in order to give different relations to the power in different positions of the armature, a portion of which moves laterally through the magnetic field or alongside of instead of directly toward 45 and from the corresponding surface of the pole, and, if required, another portion of said armature moves toward and from its corresponding pole-surface in the usual manner if brought into the range of powerful attractions by the 50 laterally-moving portion. These two portions of the armature make a channel, which receives the magnet-pole within it when the armature is attracted.

Fig. 4 represents a modification in which the 55 armature is pivoted at a distance from the

pole of the magnet, instead of being pivoted directly upon the said pole, as in Fig. 1; but the construction is substantially the same, and the armature and pole have the same portions co-operating in the same manner and indicated 60 by the same reference-letters.

In the construction shown in Fig. 4 the armature has an effective movement through an angle of ninety degrees, and might be employed, for example, to turn a damper for the 65 purpose of controlling a fire, the armature being connected directly with the damper-spline.

A magnet and armature of this kind is especially useful wherever it is desirable to actuate the part of an apparatus with a reciprocating angular movement of great range without intervening mechanism, being for such purposes far more effective than magnets of the solenoid construction, which are commonly employed where a rectilinear movement of long range is required. It is obvious that the long angular movement may be caused to produce a rectilinear movement by connecting mechanism, just as the long rectilinear movement of 80 a solenoid may be made to produce an angular movement, and a magnet of the herein-described construction may be preferable in many cases where rectilinear movement of the actuated part is required. 85

I claim—

1. The combination, with an electro-magnet having a pole-piece with converging surfaces, of an armature composed of two portions, one of which is arranged and moves substantially 90 parallel with one of the surfaces of the pole-piece, and the other of which portions approaches and recedes from the other surface of said pole-piece, substantially as described.

2. A horseshoe electro-magnet having two 95 similar pole-pieces, each provided with pivot-lugs at one side, combined with an armature pivotally connected with said lugs having two portions, one substantially radial to the pivot-axis and the other substantially concentric 100 with said pivotal axis, substantially as, and for the purpose described.

In testimony whereof I have signed my name to this specification in the presence of two subscribing witnesses.

FREDERICK W. COLE.
